SCOTCH BLOCK

Stanley W. Hayes, Richmond, Ind., assignor to
 Hayes Track Appliance Company, Richmond,
 Ind., a corporation of Indiana

Application November 2, 1939, Serial No. 302,498

6 Claims. (Cl. 104—258)

The present invention is directed to the improvement of car wheel stops of the type commonly known as Scotch blocks or the like used on railway tracks. It is directed particularly to 5 Scotch blocks of the type disclosed in Patent No. 1,801,917 granted to the present applicant, which are slidably mounted upon rails and provided with portions extending below the base of the rail into the plane of the rail-supporting ties 10 for transmission of the shock of impact to the road bed.

Scotch blocks constructed in accordance with the disclosure of the above-mentioned patent provide a cushion stop for the car wheels. This 15 results from the fact that the force of the car wheel impact is transmitted to and effects a slight movement of the ties in the road bed. It is this slight movement that provides a cushion-like shock absorbing resistance which minimizes 20 damage to either the cars or rails. The blocks are applicable to rails without the necessity of drilling either the blocks or the rails and are designed for application to rails of different sizes.

It is the object of the present invention to provide 25 a simplified wheel stop of this type having greater strength and adapted to be manufactured at lower cost.

Other objects and advantages of the invention 30 will become apparent from the ensuing description in the course of which reference is had to the accompanying drawings, in which:

Fig. 1 is a perspective view showing a pair of 35 Scotch blocks constructed in accordance with the present invention mounted in place upon the track;

Fig. 2 is a side elevational view on a larger scale of one of the blocks;

Fig. 3 is a plan of Fig. 2;

Fig. 4 is a front elevation of the block of Figs. 40 1 to 3, inclusive;

Fig. 5 is a vertical sectional view taken along the line 5—5 of Fig. 4; and

Fig. 6 is a perspective view of the tie abutting saddle utilized in the construction of the 45 block.

Referring now to the figures, the Scotch block, indicated generally by reference character 10, may be seen to comprise a pair of identical side plates 12 cut from plate steel of one-half inch 50 thickness. The plates are secured together at their front ends and spread divergently or obliquely apart at their rear ends, thereby to form a tapered structure. The front ends are secured together by welding them to a plurality of variously shaped spacing blocks 14, 16, 18, 20 and 22

placed between the plates in the manner clearly indicated in Figs. 2 and 5, particularly the latter. Additional spacing blocks may be utilized if desired. The forward ends of the plates are seated upon the rail and the spaced apart rear ends are welded to an inverted substantially U-shaped rail saddle or bracket 26, hereinafter referred to as a saddle, cut from steel plate one inch thick. This is best done by terminating the rear ends 28 of the plates 12 in vertically disposed surfaces so 10 that these may be welded to the front face 30 of the saddle 26.

The saddle extends well below the base of the rail so as to be in a position to transmit the force of the impact of a car wheel against the block 15 to the tie and ballast. The saddle is made sufficiently wide so that the force of the impact is distributed over a considerable portion of the tie face. The saddle 26 also provides a means for centering the rear end of the block upon the rail, 20 and the downwardly extending portions 32 are dimensioned so that the saddle fits over the largest size rail for which the block is designed. More specifically, the portions 34 are spaced apart far enough to fit over the largest size rail 25 base and the portions 36 are spaced apart a sufficient distance to fit over the largest size rail head.

Additional strength and rigidity are given to the block by a center plate 38 of generally triangular shape. The base of this triangularly shaped center plate is welded to the transverse portion 40 of the saddle and the converging sides are welded to the plates 12 in the same manner as the spacing blocks. The center plate is also 35 disposed at an angle with respect to the rail, as best shown in Fig. 5.

The wheel abutment 42 is formed, as may be noted from Figs. 3 and 4, of a width greater than the combined widths of plates 12, by cutting the 40 plates back from their line of contact; i. e., the line from which their divergence commences and which passes between the upper and lower parts of contact of the plates. This construction eliminates all unnecessary stresses in the plates 45 and provides an abutment of a width sufficient to engage a considerable portion of the car wheel and at the same time permits the use of relatively thin plates. The abutment has a curvature corresponding to the contour of the car 50 wheel and the block itself has a height substantially equal to the distance the car wheel axle extends above the rail.

The front or abutment end of the block is secured to the rail by non-cramping clamping 55

means 44. This clamping means comprises an openable loop structure adjustably supported from the plates by a pin 46 extending through the plates and apertured at its ends for the reception 5 of a pair of parallel vertically disposed bolts 48 secured together at their lower ends by a cylindrical cross bar 50 welded thereto. A spacer 51 is welded to pin 46 to prevent pin 46 from moving transversely of the wheel stop. Nuts 52 are 10 threaded to the upper ends of the bolts and provide a means for drawing the cross bar 50 into engagement with the under sides of rails of different size. The cross bar 50 is forced to travel in unison with the block by means of a pair of 15 eye bars 54 so as to prevent binding of the cross bar against the lower surface of the rail base. To accomplish this end, the bolts 48 are passed through the eyes 56 of the eye bars, and the offset portions 58 of the latter are hooked through 20 apertures at the lower ends of the divergent plates 12.

The front or abutment end of the block is centered upon the rail by a pair of eccentrically bored centering blocks 60, adjustably mounted upon 25 downwardly extending pins 62 by means of fixed horizontal pins 64. The pins 62 extend nearly to the tops of and are welded to tubular blocks 66 welded in turn to the outer surfaces of the plates 12. The described construction of the 30 front end centering means provides an easy means for centering the front end, as this can be accomplished simply by changing the angular positions of the blocks so that they always substantially abut against the sides of the rail head.

From the above detailed description of the 35 Scotch block of the present invention, it may be seen that the block may be constructed for the most part from metallic plate. The plate itself can be cut by means of a torch or otherwise into 40 pieces having substantially the contours illustrated and described. After the cutting of the pieces, they may be readily assembled and welded together to form a Scotch block of great strength. Furthermore, the block may be fabricated very 45 economically.

In the installation of the block, the side bolts and lower cross bar of the openable loop structure are removed, and the block set on the rail with the rear face of the saddle near or against 50 the tie. The front end of the block is centered by turning the eccentric spacing blocks on their pivots to provide a rail receiving space suited to the particular rail. The lower cross bar of the yoke is passed under the rail and connected by 55 the side bolts to the top bar after the vertically disposed rods 48 have been properly positioned. It is customary to use the blocks in pairs as illustrated in Fig. 1, the members of which are located opposite each other in the track but are unconnected, each block being supported wholly by its 60 engagement with the rail upon which it is mounted.

In operation, the Scotch block, being properly centered and held upright on the rail, transmits 65 the impact on the front end thereof to the saddle through the side plates, and the latter in turn transmits the stress of the impact to the tie. The tie yields more or less, depending upon the nature of the ballast, to provide what has been previously 70 termed a cushion stop.

What I claim as new and desire to secure by United States Letters Patent is as follows:

1. A Scotch block comprising two united plates with their front ends overlying the top of the 75 rail and their rear ends flanking and extending

below the base of the rail, a rail saddle consisting of a substantially U-shaped plate connecting the rear ends of said plates, said saddle resting upon and straddling the rail, and means for holding the front end of the block on top of the rail. 5

2. A Scotch block comprising a pair of obliquely disposed united plates with their front ends overlying the top of the rail and their rear ends flanking and extending below the base of the rail, a rail saddle consisting of a substantially U-shaped 10 plate connecting the rear ends of said plates, said saddle resting upon and straddling the rail, a center plate disposed above the rail and connecting said pair of plates, and means for holding the front end of the block on top of the rail. 15

3. A Scotch block adapted to seat on and straddle a rail and slide thereon under car wheel impact, including a pair of obliquely disposed plates having their front ends overlying the top of the rail and their rear ends flanking and extending 20 below the base of the rail, said front ends being contoured to receive the wheel and said rear ends terminating in vertically disposed surfaces, means connecting the front ends together, means for holding the front end of the block on top of the 25 rail, and a rail saddle resting upon and straddling the rail and consisting of a substantially U-shaped plate welded in inverted position to said vertically disposed surfaces for connecting the rear ends of the plates together. 30

4. A Scotch block adapted to seat on and straddle a rail and slide thereon under car wheel impact, including a pair of obliquely disposed plates having their front ends overlying the top of the rail and their rear ends flanking and extending 35 below the base of the rail, said front ends being contoured to receive the wheel and said rear ends terminating in vertically disposed surfaces, means connecting the front ends together, means for holding the front end of the block on top of the 40 rail, a rail saddle resting upon and straddling the rail and consisting of a substantially U-shaped plate welded in inverted position to said vertically disposed surfaces for connecting the rear ends of the plates together, and a center plate having 45 oblique sides welded to said pair of plates above the surface of the rail.

5. A Scotch block adapted to seat on and straddle a rail and slide thereon under car wheel impact, including a pair of obliquely disposed plates 50 having their front ends overlying the top of the rail and their rear ends flanking and extending below the base of the rail from points slightly above the top of the rail, said front ends being contoured to receive the wheel and said rear ends 55 terminating in vertically disposed surfaces, means connecting the front ends together, means for holding the front end of the block on top of the rail, a rail saddle resting upon and straddling the rail and consisting of a substantially U-shaped 60 plate welded in inverted position to said vertically disposed surfaces for connecting the rear ends of the plates together, and a center plate having oblique sides welded to said pair of plates and 65 said U-shaped plate above the surface of the rail. 70

6. A Scotch block adapted to seat on and straddle a rail and slide thereon under car wheel impact, including a pair of obliquely disposed plates having their front ends overlying the top of the rail and their rear ends flanking and extending 75 below the base of the rail from points slightly above the top of the rail, said front ends being contoured to receive the wheel and said rear ends terminating in vertically disposed surfaces, means connecting the front ends together, means for 70

holding the front end of the block on top of the rail, said last mentioned means comprising a pin extending through the plates above the rail and a spacer welded to said pin for preventing lateral movement thereof, a rail saddle resting upon and straddling the rail and consisting of a substantially U-shaped plate welded in inverted

position to said vertically disposed surfaces for connecting the rear ends of the plates together, and a center plate having oblique sides welded to said pair of plates and said U-shaped plate above the surface of the rail.
